DESIGN FOR A CLIP FOR NECKTIE KNOTS

Robert A. Lester, West Orange, N. J.

Application January 31, 1935, Serial No. 55,163

Term of patent 3½ years

To all whom it may concern:

Be it known that I, Robert A. Lester, a citizen of the United States and a resident of Hutton Park, West Orange, in the county of Essex and State of New Jersey, have invented a new, original, and ornamental Design for Clip for Necktie Knots, of which the following is a specification, reference being had to the accompanying drawing, forming part thereof.

I claim:

The ornamental design for a clip for necktie knots, as shown.

ROBERT A. LESTER.
